UNITED STATES PATENT OFFICE.

MYRON H. KINSLEY, OF WALLINGFORD, CONNECTICUT, ASSIGNOR TO THE ONEIDA COMMUNITY, (LIMITED,) OF LENOX, NEW YORK.

DESIGN FOR A SPOON OR FORK HANDLE.

SPECIFICATION forming part of Design No. 12,307, dated June 14, 1881.

Application filed May 2, 1881. Term of patent 7 years.

To all whom it may concern:

Be it known that I, MYRON H. KINSLEY, of Wallingford, in the county of New Haven and State of Connecticut, have invented a new Design for a Spoon or Fork Handle; and I do hereby declare the following, when taken in connection with the accompanying drawing and the letters of reference marked thereon, to be a full, clear, and exact description of the same, and which said drawing constitutes part of this specification, and represents a face view.

This invention relates to a design for spoon and fork handles; and it consists in the ornamentation, as shown in the accompanying illustration.

In outline the handle gradually expands from the narrower portion toward the end, terminating in a semicircular tip. On the surface, at the tip, is a bead of reverse curve, with points radiating from the center toward the bead, and also points outside the bead radiating onto the handle, giving to the tip a spherical shape. Below the tip ornamentation, and so as to leave a space, a band extends diagonally across from

edge to edge. This band is composed of a bead at the top and bottom, with a herring-bone ornament on the surface between. Below this diagonal band is a transverse band, and below that ornamentation giving a Gothic termination to the plain surface below. Between the diagonal and transverse band is the representation of rays springing from the lower angle, and a branch of flag with the representation of a stork flying, all as shown in the accompanying illustration.

35

I claim—

The herein-described design for spoon and fork handle, consisting of the semicircular-shaped tip, with semicircular bead and radial points on the surface, the ornamented band diagonally across the face, a transverse band below, with the representation of a flying stork on the surface between said bands, all as shown in the accompanying illustration.

MYRON H. KINSLEY.
